J. Brown.

Serrer.

No 79199

Patented Jun. 23, 1868.

John Brown

United States Patent Office.

JESSE BROWN, OF SAN FRANCISCO, CALIFORNIA.

Letters Patent No. 79,199, dated June 23, 1868.

IMPROVEMENT IN SEWERS.

The Schedule referred to in these Letters Patent and making part of the same.

TO ALL WHOM IT MAY CONCERN:

Be it known that I, JESSE BROWN, of San Francisco, in the county of San Francisco, and State of California, have invented a new and improved Mode of Draining Privy-Vaults, by the use of a protective cap, to prevent sewers from choking and clogging up, instead of grates or screens heretofore and now used, which is the most easy, and cheapest, and the most convenient and durable of all methods of keeping privies cleaned of their contents, and which is equally well adapted to filtration, fermentation, and disintegration, wherever it may be used and applied; and the following is a general description thereof.

My invention consists of a protective cap, which is constructed in the shape and form of the accompanying drawing, of brick, red-wood, metal, or other materials that are not subject to decomposition by ammonia, of such dimensions and size, and so adjusted, as to afford the necessary protection, and form the requisite channels to accomplish the object proposed.

The protective cap is a hollow, rectangular box, of a length much greater than its depth or breadth, but which may be varied in all its parts to fit the locality to which it is applied. Its plane and inner face is uncovered and open. Its two corresponding side faces have a right angle, at the necessary and proper distance from each end, cut down to about one-half the entire depth, causing the outer face to have and exhibit a plane of about one-half its length, with an ascending right angle of half its depth, followed by another plane of about one-half its length, which, in practical use, will vary, to adjust itself to any locality. The outer surface or covering of the lower plane projects upward at a right line with and under the upper plane a short distance, but, as far as is practically necessary, leaving and forming an open channel at the ascending angle, of the full length and breadth of the angle. The two ends of the protective cap are covered.

In order that those skilled in the arts may be able to construct my invention, I will proceed more fully to describe its construction and application, reference being had to the accompanying drawings, making part of this specification, in which—

Figure 1 is a section at the line A-B in fig. 2, shown in perspective.

Figure 2, a plan, showing the vaults D, A A, made of brick or other materials.

Figures 3 and 4, top and side view of the protector.

The same letters in the different figures represent the same things in the different figures.

A A is part of the vault.

B is the protector, made of suitable materials.

C C showing the channel for the decomposed fluid to escape.

D, the coarse stuff in the vault.

D¹ represents decomposed strata.

D² specifies heavy pieces at the bottom.

E E, the sewer, to carry off the fluid.

The protective cap stands upon the floor of a vault, on the lower end of its thinnest plane, lengthwise, and perpendicular to an inner face of a privy-wall or other wall to which it is applied, to which it is firmly attached, so that its cavity covers centrally the mouth of the sewer, through which the water and slush pass from a privy-vault, and through which other substances pass from other vaults. The entire lower plane of the protective cap, together with its sides and outer face, from the floor of the vault to its vertex, covered beneath the upper plane within the angle or channel, performs the double office of forming a channel to the within mouth of the sewer, and of protecting it from choking or clogging by the approach and contact of heavy substances; and the upper plane of the protective cap, being half its entire length deeper than its lower plane, performs the double office of forming a channel, at its angle, of its entire breadth and half its depth, exclusive of the thickness of its walls or partition, along the outer upper surface of the back of the lower plane, and the lower portions of the inner surface of the sides and back of the upper plane, to and over its vertex, into the channel formed by it and the wall, through which, when the surface of the substance, as in the privy-vault or other vaults, rises to

a line above the vertex of the lower plane, the water and slush pass on their way to the mouth of the sewer, and the upper plane extends down as far below the within vertex of the outer wall or partition of the lower plane, that none of the approaching floating substances, deposited in the vault, can pass through the channel formed by it and the lower plane into the mouth of the sewer.

My invention will be more readily understood, and its utility more generally appreciated, by statement of the following facts, to wit, that the contents of all privy-vaults naturally divide themselves into three parts, viz, first, the light upper and cloggy substances, which are always floating upon the surface; second, the middle part, being constantly increased by the decomposing matter formed by the upper floating substances, amounting to more than nine-tenths of the contents of all privies, and consisting of a slushy, watery substance, which will, if properly protected from the immediate approach of the stuff, readily find its way through the channels, into and through the mouth of the sewer; third, the lower part of the contents of a privy-vault consist of heavy substances, such as sand, broken glass, crockery, metal, &c., &c., which will, without the use of the protective cap, soon obstruct the sewer. But by using the protective cap, if the waste and rain-water from the dwelling-house were caused, by proper pipes, to pass into the privy-vaults, it would never require to be cleaned, nor would a harbor ever be perceptibly filled up by sewers protected in this way.

What I claim to be my invention, and desire to secure by Letters Patent, is—

The protective cap, when constructed and arranged as described, so as to secure the upper and lower drains of privies, as set forth.

JESSE BROWN.
